Jacob Beesley and Edward Delany of Philadelphia, Pa.

Assignors to

William P. Cresson of same place

Letters Patent No 485 Dated Aug. 10th, 1852

The schedule referred to in these Letters Patent and making part of the same

To all whom it may concern:

Be it known that we Jacob Beesley and Edward Delany, of the City of Philadelphia, in the County of Philadelphia, and State of Pennsylvania, have invented or produced a set of new and original designs to ornament a nine plate Stove, and we do hereby declare that the following is a full and exact description of the same.

Fig 1 Represents the side plate with the oven door, a, laid in its place, - The whole door forms a panel with a rosette, b, in the centre, around which is scroll work as at c, c, c, c, outside of which is an edging of a peculiar form as at d, d, d, outside of edging is beading, squares & coves to the outer rim of the door as at E, E, E, E, lower down on the plate is a horizontal panel of similar form with a rosette in the centre as f, around which is scroll work as at g, g, g, g, outside of which is the same design of edging as on the door above described as at h, h, h, h, outside of edging is a series of beads, coves & squares to the outer edge of the panel as at i, i, i, i, the rim of the plate is ornamented with an edging of a waved form as at K, K, K, K.

Fig 2 Represents the front plate with the feeder door, l, in its place, this whole door forms a panel ornamented with scrollwork m, m, beading, coves & squares to the outer edge as at n, n, n, n, above the door is an upright panel with coved corners, in the centre of which is a rosette o, around which is scroll work p, p, p, p, outside of which is beads, squares & coves to the edge of the panel as at q, q, q, q, outside of this portion of the plate say immediately around the feeder door, and upright panel above the door is ornamented with the same design of waved ornaments as figure 1. See in this plate N, N, V, V, on each side of this plate is a slightly raised pilaster each ornamented with three very flat beads terminating at the head with a round end S.

Fig 3 Represents the back plate ornamented in the middle with an upright panel with coved corners the centre of the panel is ornamented with a rosette t, of peculiar form around which is scrollwork as at u, u, u, u, the edge of the panel being ornamented with beads squares & coves as at V, V, V, V, around the panel on this portion of the plate is the same waved edging as around Figure 1. u, u, u, and the sides of this plate having the same design and form as Figure 2, see x, x.

What we Claim as our invention and desire to secure by Letters Patent is, the ornamental designs for a nine plate stove as herein described and represented, in the annexed drawings
